UNITED STATES PATENT OFFICE.

HERVEY M. WILSON, OF FULLERTON, NEBRASKA.

PIPE-WRENCH.

SPECIFICATION forming part of Letters Patent No. 338,326, dated March 23, 1886.

Application filed December 23, 1885. Serial No. 186,559. (No model.)

To all whom it may concern:

Be it known that I, HERVEY M. WILSON, a citizen of the United States, residing at Fullerton, in the county of Nance and State of Nebraska, have invented a new and useful Improvement in Pipe-Wrenches, of which the following is a specification, reference being had to the accompanying drawings.

My invention relates to improvements in pipe-wrenches; and the novelty consists of the peculiar construction and combination of parts, substantially as hereinafter fully described, and specifically pointed out in the claims.

15 The primary object of my invention is to provide a wrench for holding pipes, rods, and other like cylindrical objects, which shall be very simple, strong, and durable in construction, and to provide means whereby the pivoted jaw can be adjusted to open to any desired extent for the purpose of grasping objects of different diameters.

20 A further object of my invention is to provide a wrench which shall be capable of easy operation and adjustment, and which shall be cheap of manufacture.

25 In the accompanying drawings, Figure 1 is a perspective view of a wrench embodying my invention. Fig. 2 is a view of the wrench showing the pivoted handle-lever and the pivoted grasping-jaw distended. Fig. 3 is a sectional view on the line *xx* of Fig. 2.

30 Referring to the drawings, in which like letters of reference indicate corresponding parts in all the figures, A designates a pipe-wrench constructed in accordance with my invention, and having a rigid toothed or serrated jaw, B, having an extended handle, *b*, a bracket, C, a pivoted adjustable clamping-jaw, D, a pivoted lever, E, and a spring, F, for forcing the lower end of the pivoted jaw D normally outward, the peculiar construction and arrangement of the several parts above designated being presently described. The bracket C is arranged at right angles to and rigidly secured on the rigid jaw B of the wrench, and the parallel side arms thereof are slotted longitudinally, as at *c*, in which work the trunnions or pivot-pins *d* of the clamping-jaw D. These pivot-pins of the clamping-jaw are arranged on opposite side faces of the jaw at or near the middle thereof, and said jaw is

arranged and adjustable back and forth between the parallel arms of said bracket, the trunnions *d* serving as pivots and guides to the 55 adjustable pivoted jaw in its various adjustments and movements. The inner face of said adjustable jaw is toothed or serrated, as shown, and the upper toothed end is arranged opposite to the serrated portion of the rigid jaw B. 60 The lower end of the pivoted jaw D is provided with curved spaced apart lugs *d'*, between which is pivoted a bent arm, *e*, of an operating-lever, E, said lever being pivoted near its upper end to the outer ends of links G, which in 65 turn are pivoted on the handle *b*, as at *g*. The lower end of the spring F is rigidly secured to the handle-bar *b*, and the opposite end of said spring is left free and bears against the pivoted adjustable jaw D, at a point intermediate between its point of connection with the lever E and the bracket C, to force the said jaw normally away from engagement with the rigid jaw.

I designates an adjusting-screw, which works 75 in a threaded socket of the bracket C, and bears against the adjustable clamping-jaw D. When the screw is turned inwardly, the adjustable jaw D is forced nearer to the rigid jaw B and against the tension of the spring F, 80 and when the said screw is turned outwardly the spring forces the adjustable jaw away from the rigid jaw to enlarge the opening or space between the jaws and adapt them to hold or grasp pipes, &c., of different diameters. 85

To open the jaws to grasp a pipe, &c., the lower end of the handle-lever is forced outwardly, which thus moves on its pivot and draws the upper end thereof inwardly toward the rigid jaw, which inward movement of the upper end of the lever causes the adjustable jaw D to oscillate or turn on its pivots or trunnions, the lower end moving inward with the lever E, and the upper serrated end moving outwardly away from the rigid jaw to 95 adapt the jaws to clamp a pipe, &c. After the jaws engage a pipe or the like, the lower end of the handle-lever E is drawn inward toward the handle-bar, which causes the serrated jaws to take a firm and secure hold.

I attach especial importance to the pivoted handle-lever and the spring-actuated movable jaw pivoted thereto, and to a bracket at a point intermediate between the lower and up-

per ends thereof, as by such construction I provide a wrench which possesses the important requisites of a double leverage, which is capable of operation with a minimum of force, 5 and secures a maximum degree of grasping or holding force between the jaws.

Having thus fully described my invention, what I claim as new, and desire to secure by Letters Patent, is—

10 1. In a wrench, the combination of a rigid jaw, a lever pivoted to the rigid jaw, a pivoted jaw pivotally connected to the lever and movable laterally of the rigid jaw, and a spring for normally forcing the movable jaw away 15 from the rigid jaw, substantially as described.

15 2. In a wrench, the combination of a rigid jaw carrying a bracket, a lever, a movable jaw pivoted to the bracket and to the rear end of the pivoted lever, a spring bearing against 20 the movable jaw at a point intermediate of the

pivots thereof, and a screw for regulating the adjustment of the movable jaw, substantially as described.

3. As an article of manufacture, a wrench comprising a rigid jaw having a handle, *b*, a 25 slotted bracket, *C*, secured thereon, links *G*, pivoted to the handle *b*, a lever, *E*, pivoted to the links, a laterally-adjustable jaw, *D*, having trunnions working in the slotted bracket and pivoted at its lower end to the lever *E*, a spring, 30 *F*, and an adjusting-screw, *I*, substantially as described.

In testimony that I claim the foregoing as my own I have hereto affixed my signature in presence of two witnesses.

HERVEY M. WILSON.
